UNITED STATES PATENT OFFICE.

PERCY R. DRENNING, OF BALTIMORE, MARYLAND, AND ERNEST F. MECHLIN, OF WASHINGTON, DISTRICT OF COLUMBIA, ASSIGNEES, BY MESNE ASSIGNMENTS, TO THE SYMINGTON COMPANY, A CORPORATION OF MARYLAND.

DRAFT RIGGING.

Application filed May 3, 1922. Serial No. 558,190.

To all whom it may concern:

Be it known that we, PERCY R. DRENNING and ERNEST F. MECHLIN, citizens of the United States, residing at Baltimore, State 5 of Maryland, and Washington, District of Columbia, respectively, have invented certain new and useful Improvements in Draft Rigging; and we do hereby declare the following to be a full, clear, and exact description of the invention, such as will enable others skilled in the art to which it appertains to make and use the same.

This invention relates to draft rigging for railway cars.

15 The invention has for an object the provision of simple, durable and inexpensive draft rigging involving a horizontal yoke formed with a key receiving rear end, said rear end being slotted and reinforced to 20 provide a buffing construction in which the backstop is eliminated.

25 Another object of the invention is to provide a draft rigging including in combination a standard two-key and three-key arrangement wherein the draft benefits of the two-key construction are maintained and an economical buffing construction of the three-key type is provided without the use of a backstop casting.

30 A further object of the invention is to provide in combination a yoke having a key receiving end, and a stop casting, the stop portion thereof projecting inwardly of the draft sills and arranged in longitudinal 35 alignment with and overlying a portion of the yoke, whereby the full area of the rear key is put under compression upon buffing movement.

40 The invention further consists in the arrangement and construction of the several parts, as will be hereinafter fully described and pointed out in the claims.

45 In the drawings wherein I have illustrated an embodiment of my invention and wherein corresponding reference characters designate similar parts in the several views:

50 Figure 1 is a view half in plan and half in horizontal section, of the center draft sills showing my improved rear end construction of the yoke and associated key.

Figure 2 is a vertical longitudinal section view on the line 2—2 of Figure 1.

Figure 3 is a transverse vertical sectional view on the line 3—3 of Figure 2.

Figure 4 is a transverse vertical sectional view on the line 4—4 of Figure 2.

Figure 5 is a detail horizontal sectional view through a portion of the rear of the yoke and adjacent center sill.

The spaced center or draft sills are indicated by the numeral 1. A conventional striking casting and coupler carry iron are indicated at 2, and the coupler at 3. These parts may be of any suitable or desirable construction.

Each sill 1 is provided with a plurality of longitudinally extending slots, and to the outer face of each sill is connected a cheek plate 4 formed with a plurality of longitudinally extending slots 8, 9 and 10 arranged to register with the slots in the sills when the cheek plates are in position. Each cheek plate is preferably provided with inwardly extending bosses 5, 6 and 7, respectively, arranged to surround the edges of the slots 8, 9 and 10 longitudinally arranged in the sills 1. Laterally and outwardly extending bosses 11, 12 and 13 are formed on the cheek plates, said bosses being arranged to surround and form, together with the aforesaid bosses, the key receiving slots 14, 15 and 16 provided in each cheek plate. The outwardly extending bosses are relatively wide, and the inner faces thereof are designed to form forward and rear stop portions for the respective front and rear edges of the keys. The bosses 11 and 12 are interconnected by reinforcing webs 17, and a relatively long longitudinal rib 18 serves to connect the bosses 12 and 13. Other reinforcing webs or ribs 19 may be provided at the respective ends of the cheek plates, terminating in the bosses 11 and 13, respectively. The cheek plates are firmly connected to the center sills by means of a plurality of rivets 20.

The rear end of each cheek plate is provided with an inwardly projecting portion 21 arranged to extend through the slot 7 in the center sill, said portion forming a rear stop lug of a width substantially equal to the clearance between each yoke arm and the inner face of the center sill.

A yoke 22 of the horizontal type is shown, said yoke being connected to the coupler 105 by means of the coupler key 23. The coupler key 23 passes through slots 24 formed in the forward end of the yoke arms,

the forward portion of said slots 24 being flared to provide increased bearing surfaces for the front edge of the key, and also acting as guide means for the forward end 5 of said yoke. The key 23 is adapted to slidably connect the coupler 3 to the yoke 22, said key in the normal position of the gear engaging the rear wall of the slot 25 in the coupler and engaging at its forward edges 10 against the forward ends of the slots 24 in the yoke arms, the said key being also arranged to extend through the slots 14 in the cheek plates and normally positioned at an intermediate point in said slots. It will 15 be noted that in the normal position of the parts the rear end of the slots 24 substantially coincide with the rear end of the slots 14 in the cheek plates. This construction permits an inward movement of the coupler 20 independent of the yoke under buffing stresses.

The rear end of the yoke 22 connects the side arms thereof and is provided with a key receiving slot 26, said slot being closed at each end by the transverse wall portions 27 and 28 integrally uniting said side arms. Longitudinally and diagonally disposed webs or ribs 29 form the top and bottom portions of the yoke end, said webs or ribs being further united by means of the vertically arranged flanges or webs 30, as clearly shown in Figure 4. This arrangement of ribs and flanges serves to reinforce and brace the wall 27 when resisting buffing stresses, and also provides a relatively light and hollow web construction of maximum strength value. A construction of rear yoke end, such as shown, can be readily and inexpensively cast, as will be understood. The top and bottom portions of the rear end of the yoke are preferably curved, as shown, thereby providing a relatively large and correspondingly strong construction, the largest vertical diameter of which is arranged centrally of the yoke and engages the cushioning mechanism, illustrated diagrammatically by the dot and dash lines in Figure 1.

Figure 11
Formed upon each yoke arm at the rear of
50 the yoke and adjacent the forward portion
of the key receiving opening or slot 26, is
a lug or projection 31 having a key engaging
portion 32 adapted to contact the forward
edge of the rear key 33 upon buffing move-
55 ment. The projection 31 upon each yoke
arm is arranged relatively close and adja-
cent the inner face of each center sill, said
projection being of a width equal substan-
tially to the clearance between the respec-
60 tive yoke arms and center sills. Each pro-
jection 31 is arranged in longitudinal aline-
ment with the inwardly projecting portion
21 provided on the cheek plate and extend-
ing through the center sill, as hereinbefore
65 described. The respective lugs or projec-

tions 31 are also arranged to overlie the said projecting portions 21, thereby providing for the full compression of the rear key upon buffing movement. The projections 31 are provided with guide or bearing faces 70 34 adapted to contact the inwardly projecting boss of the cheek plate and the inner face of each center sill, thereby providing guide means for the rear end of the yoke for preventing undue lateral movement 75 thereof. Portions of the bearing face 34 extend rearwardly above and below the rear key, the extreme innermost ends of said bearing faces being beveled inwardly, as shown. The forward ends of the inwardly projecting lugs or portions 21 formed on the cheek plate, are also inclined, as shown, for cooperation when buffing, with the beveled end portions 35 on the rear wall 28 of the yoke. 80 85

The forward end of the cushioning mechanism cooperates with the key connected follower 36, said follower comprising a plurality of vertically and longitudinally arranged reinforcing ribs 37. The follower 36 is preferably of the same general contour as the rear end of the yoke. The opposed faces of said follower and the rear of the yoke are relatively large for engaging the cushioning mechanism, the said large portions tapering forwardly and rearwardly, respectively, to substantially the vertical height of the yoke arms and coupler stem, as shown. A key 38 extends through the slot 39 in the follower 36, the key ends projecting laterally through the relatively long slots 40 in the yoke arms, and the slots 15 in the cheek plates hereinbefore mentioned.

A draft rigging of the type set forth provides for the pulling benefits incident to a standard two-key construction, and at the same time permits of the use of a third key, said key and integral rear end of the yoke cooperating with a rear stop member on the cheek plate thereby providing an inexpensive and effective buffering construction in which the usual backstop is eliminated. On buffering movement it will be seen that the lugs 31 on each yoke arm engage the forward edge of the rear key and, together with the inner face of the wall 27 also engaging the forward edge of said key, moves said key rearwardly until the rear edge thereof contacts the rear stop portions of the bosses 13 and the inwardly extending projections 21 formed on the cheek plates. The buffering stresses are imparted through the wall 27 and projecting lugs 31 which place the key under compression, the inwardly projecting stop portions 21 acting to prevent shear strains from being imparted to said rear key. On forward movement of the yoke, the wall 28 closing the rear of the key receiving opening acts to move the rear

key forwardly of the cheek plate and center sill slots, as will be understood.

We claim:

1. In a draft rigging, the combination with spaced center sills, of a cushioning mechanism, a coupler, a horizontal yoke having a key receiving opening in the rear end thereof, means connecting said coupler and yoke, rear stop members connected to the center sills and having portions projecting inwardly thereof, a key passing through said key receiving opening and adapted to have the rear edge thereof engage said stop members on buffing movement, and means carried by said yoke and arranged adjacent the forward end of said key receiving opening for engaging the forward edge of said key, said means being adapted to contact the center sills for guiding the yoke and overlie the inwardly projecting portions of the rear stop members. 10
2. In a draft rigging, the combination with spaced center sills, of a cushioning mechanism, a coupler, a horizontal yoke having a key receiving opening in the rear end thereof, means connecting said coupler and yoke, rear stop members connected to the center sills and having portions projecting inwardly thereof, a key passing through said key receiving opening and adapted to have the rear edge thereof engage said stop members on buffing movement, and projecting lugs carried by said yoke adjacent the forward end of said key receiving opening, said lugs having key engaging faces overlying the inwardly extending portions of said rear stop members, and also provided with bearing surfaces for engaging the inner faces of said center sills. 20
3. In a draft rigging, the combination with spaced center sills, of a cushioning mechanism, a coupler, a yoke having a closed key receiving slot in the rear end thereof, a coupler key connecting said yoke and coupler, a key connected follower arranged between said coupler and cushioning mechanism, a key passing through the key receiving slot in the rear of said yoke, cheek plates connected to said center sills and having an inwardly projecting stop portion for the rear edge of said last named key, and means carried by the rear end of said yoke and adjacent said key receiving slot for engaging the forward edge of said last named key and contacting the inner faces of said center sills. 30
4. In a draft rigging, the combination with spaced center sills, of a cushioning mechanism, a coupler, a yoke having a closed key receiving slot in the rear end thereof, a coupler key connecting said yoke and coupler, a key connected follower arranged between said coupler and cushioning mechanism, a key passing through the key receiving slot in the rear of said yoke, a 40
- cheek plate connected to the outer face of each center sill and having a plurality of slots, a key passing through the key receiving slot in the rear of the yoke and extending through oppositely registering slots in said cheek plates, means adjacent the rear stop portion of said cheek plates with which the rear edge of said last mentioned key engages on buffing movement, said means being carried by said cheek plates and extending through the center sills, and means carried by the rear end of said yoke adjacent the forward portion of said closed key receiving slot for engaging the front edge of said last named key. 50
5. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key having portions projecting inwardly of the draft sills, means connecting said coupler to the forward end of said yoke, means for guiding the forward end of said yoke, and means contacting the inner faces of said draft sills for guiding the rear end of said yoke, said last named means overlying the inwardly projecting portions of the stop members and adapted to engage the forward edge of the key upon buffing movement. 60
6. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means projecting from the yoke at the rear thereof adapted to contact the inner faces of said draft sills for guiding the rear end of said yoke, said last named means being arranged adjacent the forward end of said closed key receiving slot and adapted to engage the forward edge of said key in overlying relation with respect to the rear stop members. 70
7. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 80
8. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 90
9. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 100
10. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 110
11. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 120
12. In a draft rigging, the combination with spaced draft sills, of cushioning mechanism, a coupler, a horizontal yoke having a closed key receiving slot at the rear end thereof, a key slidably connecting said yoke with the draft sills, rear stop members for said key, means connecting said coupler and the forward end of said yoke, means for guiding the forward end of said yoke, and means contacting the inner faces of said draft sills for guiding the rear end of said yoke, said last named means projecting outwardly from the yoke arms and arranged to overlie portions of said rear stop members for placing said 130

key under compression on buffing movement.

8. In a draft rigging, the combination with spaced center sills, of cushioning mechanism, a coupler, a yoke having parallel arms, means connecting said coupler and yoke, a key slot in said yoke arms adjacent the rear end of said yoke, a lug projecting from the outer face of each yoke arm adjacent the forward end of said key slot, and stop members with which the rear edge of said key engages on buffing movement, said stop members projecting inwardly of the center sills and overlying said lugs projecting from the yoke arms.
9. A horizontal yoke for draft rigging of the class described, having a closed key receiving slot formed between front and rear walls integrally uniting the side arms of the yoke at the rear end thereof, and a plurality of vertical flanges of diminishing height from the center of said yoke for reinforcing the front wall of said key receiving slot.
10. A horizontal yoke for draft rigging

of the class described, having a closed key receiving slot formed between front and rear walls integrally uniting the side arms of the yoke at the rear end thereof, and a plurality of longitudinally and diagonally arranged ribs located above and below said slot, said ribs being of laterally and longitudinally diminishing height from the forward center portion of the front wall uniting the yoke arms.

11. A horizontal yoke for draft rigging of the class described, having oppositely disposed parallel side arms, a closed key receiving slot extending through said arms at the rear of the yoke, and lugs projecting outwardly from said arms adjacent the forward end of said key slot, said lugs being adapted to contact the center sills of the draft rigging for guiding the rear of the yoke and disposed to overlie the rear stop members of said draft rigging.

In testimony whereof we affix our signatures.

PERCY R. DRENNING.
ERNEST F. MECHLIN.
